UNITED STATES PATENT OFFICE.

JOHN S. POTTER, OF NEWTON, AND DAVID J. CARTWRIGHT, OF BOSTON,
MASSACHUSETTS; SAID CARTWRIGHT ASSIGNOR TO SAID POTTER.

ELECTRIC-WIRE INSULATING-CLEAT.

SPECIFICATION forming part of Letters Patent No. 444,317, dated January 6, 1891.

Application filed August 16, 1890. Serial No. 362,187. (No model.)

To all whom it may concern.

Be it known that we, JOHN S. POTTER, a citizen of the United States, and a resident of Newton, in the county of Middlesex and State 5 of Massachusetts, and DAVID J. CARTWRIGHT, a citizen of the United States, and a resident of Boston, in the county of Suffolk and State of Massachusetts, have jointly invented new and useful Improvements in Wiring Insulating Cleats, of which the following, taken in connection with the accompanying drawings, is a specification.

This invention relates to improvements in wiring insulating-cleats for the purpose of suspending and holding electrical wires in place on ceilings or walls, and it is carried out as follows, reference being had to the accompanying drawings, wherein—

Figure 1 represents a top view of the improved cleat. Fig. 2 represents a bottom view of it. Fig. 3 represents a side view of the same, and Fig. 4 represents a section on the line X X shown in Fig. 3.

Similar letters refer to similar parts wherever they occur on the different parts of the drawings.

A in the figures, represents the improved cleat, which is made of insulating material, preferably of porcelain.

A' A' are vertical perforations in the cleat for the purpose of receiving the fastening-screws B B, by means of which the cleat is secured to the ceiling or wall.

A'' A'' are elevated or raised bearing-surfaces on the upper side of the cleat, through which the perforations A' A' pass, which bearing-surfaces are made on the cleat for the purpose of transferring the holding-pressure of the said fastening-screws to the places 40 where such screws pass through the cleat, and thus preventing the breakage of the latter, particularly if secured to uneven walls or ceilings, posts, &c.

At right angles to the screw-receiving perforations A' A' we make transverse perforations a' a' a', through which the electric wires C are inserted and held and supported at

proper distances from each other, as shown in Fig. 4. The said wire-holding perforations are made tapering from end to end, as shown 50 in Fig. 4, and this is done for the purpose of temporarily securing the wires to the successive cleats while such wires are being strung. Such temporary securing of the wire to the cleat is accomplished by means of a tapering 55 wedge D, preferably made of wood and driven into the larger end of the tapering hole a', so as to clamp or bind the wire within such tapering hole until the wire has been inserted through the next cleat in the series stretched 60 and temporarily secured in place when the wedge in the first cleat is removed, and so on until the whole of the line-wires are passed through the cleats.

Having thus fully described the nature, construction, and operation of our invention, we wish to secure by Letters Patent, and claim—

1. An insulating wiring-cleat formed integral on its upper surface with the elevated bearing-surfaces A'', and provided with the 70 perforations A', extending through said elevated bearing-surfaces, and with tapering wire-retaining perforations a', against the walls of which the wires are adapted to be wedged by suitable wedges, substantially as 75 described.

2. An insulating wiring-cleat for electric wires, having the elevated or raised bearing-surfaces on its upper side, and perforations passing through the cleat and such bearing-surfaces for the reception of fastening-screws for the purpose of clamping the cleat against such bearing-surfaces only, substantially as 80 specified.

3. The improved insulating wiring-cleat 85 having the elevated or raised bearing-surfaces on its upper side and perforations going through the cleat and such bearing-surfaces, combined with transverse tapering wire-retaining perforations extending at right angles 90 to the perforations which extend through the bearing-surfaces, substantially as and for the purpose set forth.

4. The improved insulating wiring-cleat

having tapering wire-retaining perforations and wires passing through the same, combined with wedges for securing said wires temporarily against the walls of said tapering perforations, substantially in a manner as specified.

In testimony whereof we have signed our names to this specification, in the presence of

two subscribing witnesses, on this 4th day of August, A. D. 1890.

JOHN S. POTTER.
DAVID J. CARTWRIGHT.
